UNITED STATES PATENT OFFICE.

BENJAMIN W. MORFOOT, OF CHICAGO, ILLINOIS, ASSIGNOR OF ONE-HALF TO
HUGO ZIEGFELD, OF MOUNT VERNON, NEW YORK.

KEY-OPENING CAN.

SPECIFICATION forming part of Letters Patent No. 621,758, dated March 21, 1899.

Application filed March 14, 1898. Serial No. 673,854. (No model.)

To all whom it may concern:

Be it known that I, BENJAMIN W. MORFOOT, a citizen of the United States, residing at Chicago, in the county of Cook and State of Illinois, have invented certain new and useful Improvements in Key-Opening Cans; and I do hereby declare the following to be a full, clear, and exact description of the invention, such as will enable others skilled in the art to which it appertains to make and use the same.

My invention relates to a novel construction in a key-opening can, the object being to provide a device of this character of extremely simple construction, small cost, and efficient operation; and it consists in the features of construction and combinations of parts hereinafter fully described and claimed.

In the accompanying drawings, illustrating my invention, Figure 1 is a top plan view of a can constructed in accordance with my invention. Fig. 2 is a sectional view of the same on the line 2 2 of Fig. 1. Fig. 3 is a top plan view showing the removable strip in the cover partly wound upon the key. Fig. 4 is a detail view showing the manner of offsetting the projecting tongue to permit the cover to be properly secured upon the box.

The principal object of my present invention is to produce a simpler and cheaper can with a key-opening head than has heretofore been produced and also to provide a head in which a removable strip is formed, which will be more reliable in operation than any which have heretofore been produced and which can be adapted to cans of any form. To these ends I provide a box A, having heads B and C, mounted in the ends of the peripheral strip D, which is slightly offset outwardly at its ends to form shoulders 1, upon which said heads B and C are adapted to rest. The depth of said offset portion is preferably about equal to the thickness of the metal, so that the outer faces of said heads will be flush with the edges of the strip D. Said heads B and C are perfectly plane and devoid of flanges, so that when soldered in place on said strip D the upper and lower faces thereof will be practically plane. Said head C of said can is provided with a peripheral removable strip 2, formed by a weakening line or incision 3, which extends from the edge of

the sheet inwardly upon the body thereof at a given distance from the periphery and is parallel with the latter except at sharp corners, where said line turns on a curve having 55 a greater radius than the small round corner of the box, thus increasing the width of the strip at the corners. In the drawings I have illustrated a usual form of sardine-box having an oblong form with small rounded corners. If 60 said weakened line were to be made parallel with the peripheral face of said box, it would obviously make a very sharp turn at the corners and would be apt to tear transversely, thus necessitating the use of an ordinary can-65 opener to open the box. By running said line farther inwardly at said corners and increasing the width of the strip at these points the tendency of the strip to tear transversely is overcome. Said weakened line terminates at 70 a point adjacent its starting-point, so as to leave a small portion of unweakened metal between such point of termination and the adjacent portion of the weakened line. This has the effect of preventing the middle portion of the head which is bordered by said weakened line from being entirely detached from said strip, which is obviously advanta-75 geous. The said head C is secured in place by means of soft solder or other similar material, and this joint forms the other weakened line bordering the removable strip. Said removable strip 2 terminates in a tongue 4, projecting beyond the edge of said head and obviously beyond the periphery of said box. 80 The said tongue 4 is offset upwardly, as at 5, to permit said head to fit within said offset portion of said strip D. Where said tongue 4 passes over the edge of said strip D, it is soldered to the latter from below, so as to 85 completely seal the can. To remove said head C, the key 6, which is adapted to lie in a depression 7 in the middle portion of said head, is inserted over said tongue 4, a slot 9 being provided in said key for the purpose, 90 and upon turning said key said strip will be torn from the edge of said strip D and along said weakened line 1 and wound upon said key in the manner shown in Fig. 3. When 95 completely torn on its soldered edge, said head will be entirely removed and leave the 100 box entirely open to permit the ready removal

of the contents without breaking, tearing, or otherwise injuring the latter and leaves no ragged edges to scratch and cut the fingers.

It will be apparent that in order to successfully operate a key-opening can-head the metal on each side of the removable strip must be braced sufficiently to withstand the strains—that is, it must not bend, but should retain its original shape and position. On one side of the removable strip 2 is the peripheral strip D, which will obviously withstand the strains, while on the interior of said removable strip 2 I have provided the depression 8, which is bordered by a bevel 10, formed in the tin, and this acts similar to a rib, bracing the metal against bending and generally stiffening the entire can-head, while the depression 7, which conforms in shape to and holds the key, also has the additional function of a lateral strengthener to the head C.

By my manner of forming the soldered joint between the can-head and the peripheral sheet I obtain a joint to tear which requires a strain so nearly equal to that required to tear the tin along the weakened line as to equalize the strain on both sides of the strip. This in particular forms the most essential part of my invention, as the equalization of the ripping strain on both sides of the removable strip is absolutely essential to the successful operation of a key-opening can. As above stated, it is also necessary that the metal on both sides of the strip be braced to prevent bending, and in considering these features in a key-opening can I provide an absolutely operative device and one which requires so little strength that a child can operate it.

It will of course be understood that though I have illustrated only a sardine-box made in accordance with my invention any other form may be made to equal advantage.

I claim as my invention—

1. In a can, the combination with a peripheral sheet outwardly offset at its outer edge to form an internally-strengthening and ribbed shoulder, of a can-head fitted and adapted to be soldered in this shoulder, said can-head having a depression bounded by a strengthening beveled portion, and having a second strengthening depression adapted to conform to and hold a key, and a line of weakness surrounding said beveled portion whereby a peripheral strip is formed for detachment all around the beveled depression and between the latter and the extreme shouldered edge of the peripheral sheet, so that the latter is firmly braced on each of its edges. 45 50 55

2. In a can, the combination with a peripheral sheet outwardly offset at its outer edge to form an internally-strengthening and ribbed shoulder, of a can-head fitted and adapted to be soldered in this shoulder, said can-head having a depression bounded by a strengthening beveled portion, and having a second strengthening depression adapted to conform to and hold a key, and a line of weakness surrounding said beveled portion whereby a peripheral strip is formed for detachment all around the beveled depression and between the latter and the extreme shouldered edge of the peripheral sheet, so that the latter is firmly braced on each of its edges and the tear of this strip is always effected simultaneously at two points intersected by a line 60 65 70 75 practically perpendicular to the inner weakened line.

In testimony whereof I affix my signature in presence of two witnesses.

BENJAMIN W. MORFOOT.
